UNITED STATES PATENT OFFICE.

JACOB EDWARD MOSEMAN, OF DONALDSONVILLE, LOUISIANA.

NON-REFILLABLE BOTTLE.

SPECIFICATION forming part of Letters Patent No. 790,700, dated May 23, 1905.

Application filed February 9, 1905. Serial No. 244,872.

To all whom it may concern:

Be it known that I, JACOB EDWARD MOSEMAN, a citizen of the United States, residing at Donaldsonville, in the parish of Ascension 5 and State of Louisiana, have made certain new and useful Improvements in Non-Refillable Bottles, of which the following is a specification.

My invention belongs in that general class 10 of bottles which are provided with attachments adapted to prevent refilling after discharge of their original contents, and it is more particularly an improvement in that special class of such bottles in which the attachment comprises a stopper permanently secured 15 in a bottle-neck and provided with a passage having a valve that will permit discharge but prevent entrance of liquid.

My invention is embodied in the construction, arrangement, and combination of parts 20 hereinafter described and claimed, reference being had to the accompanying drawings, in which—

Figure 1 is a longitudinal section of a bottle and my improved non-refillable attachment therefor. Fig. 2 is a perspective view of a stopper of modified construction.

A stopper *a* is permanently secured in the mouth of a bottle *x*, and both are preferably 30 constructed of glass, and they may be fused together or secured by any other suitable means. A tube *e* is attached to the inner end of the stopper and extends to the bottom of the bottle, it being provided at an adjacent 35 point with inlet-ports *e'*. In this tube works or slides a piston *b*, having a stem *b'*, that extends through a central passage in the stopper *a* and is provided exteriorly with a handle *b''*. It will be noted that the aforesaid inlet-openings *e'* are located a sufficient distance 40 above the bottom of the tube *e* to permit the piston *b* to pass below them, as indicated by dotted lines, Fig. 1.

The stopper *a* is provided with a circuitous 45 passage for discharge of the liquid contents of the bottle—that is to say, the passage has a vertical part *c* entering from the top of the stopper and another vertical part *c'* entering or opening in the bottom of the stopper, the 50 two parts *c c'* being located out of alinement

or on different sides of the stopper, as shown. The inner ends of the two passages *c c'*, as shown in Fig. 1, are connected by a central horizontal passage; but in the modification shown in Fig. 2 the inner ends of ports *c c'* are 55 connected by a passage *g*, (see Fig. 2,) which is preferably formed as a semicircumferential groove in the body of the stopper. By this arrangement it is evident that no tool can be inserted and successfully manipulated for access to a valve located in the passage *c'*. The valve *f* here shown seats downward at the head of such passage, and its stem is surrounded by a spiral spring *d*, by which it is held normally seated in the passage, so as to normally prevent discharge of liquid save when the tension of the spring is overcome and preventing in any case the entrance of liquid from the outside.

From the foregoing description it will now 70 be understood that in order to effect the discharge of the contents of the bottle *x* or any portion thereof the piston is pushed down until it passes below the lateral inlets *e'* of the tube *e*, as shown by dotted lines, Fig. 1, 75 whereupon liquid enters the tube above the piston and fills the same to the level of the liquid outside it. Then upon raising the piston the liquid in the tube is forced upward and acts against the valve *f* and overcoming 80 the tension of the spring *d* opens the valve, so that the liquid passes through the circuitous passage in the stopper and discharges therefrom at the point *c''*. The piston and tube thus constitute practically a force-pump, by 85 which the liquid is raised and forced out through the stopper past the valve. When the piston is again pushed down, the liquid which fills the tube below it will be forced out through the inlets *e'* into the body of the bottle, and the piston passing such inlets as before the discharging operation is repeated.

Having thus described my invention, what I claim as new, and desire to secure by Letters Patent, is—

1. The combination, with a bottle, of a stopper which is permanently secured thereto and provided with a circuitous passage for discharge of liquid, a valve seated in the lower portion of such passage and provided with a 100

spring which holds it normally seated downward therein, a tube connected with the stopper and extending to the bottom of the bottle and provided at a point adjacent to the latter

5 with lateral inlets, and a piston adapted to slide in said tube and pass below the said inlets, and provided with a stem adapted to slide in the stopper, substantially as described.

2. An attachment for non-refillable bottles, 10 comprising a stopper having a passage for discharge of liquid, and a yielding valve seated therein and normally closing the same against escape of liquid and permanently closing the same against entrance of liquid, a tube connected with the stopper and inclosing the entrance to the discharge-passage, and having in its lower portion lateral inlets for liquid, a piston adapted to slide in the said tube to a point below the inlets, and having a stem extending outward through the stopper, substantially as described.

3. The combination, with a bottle, of a stopper secured thereto, and having a discharge-passage comprising two longitudinal parts 25 which are out of alinement with each other, and a connecting - passage arranged transversely, a yielding valve seated in the lower part of such passage and seated downward,

and a force-pump connected with the stopper and serving to expel liquid from the bottom 30 by forcing it upward against the valve and past the same, substantially as described.

4. The combination, with a bottle, and a stopper secured in the mouth thereof and having a valved discharge-passage, of a force-pump comprising a tube which is secured between the stopper and the bottom of the bottle and provided with a lateral inlet and having a 35 slideable piston working in such tube and adapted to pass below the inlet and having a 40 stem sliding liquid-tight in the stopper, as shown and described.

5. The improved attachment for non-refillable bottles, comprising a stopper having a circuitous passage provided with a yielding valve seated downward in the lower portion of the passage, and a force-pump attachment comprising a tubular extension having an opening for inlet of liquid, and a piston adapted to slide therein and provided with a stem 45 50 passing through and slideable in the stopper, substantially as described.

JACOB EDWARD MOSEMAN.
